CHARLES M. STROUD, OF MINNEAPOLIS, MINNESOTA, ASSIGNOR OF ONE-HALF TO
ROLLIN E. STARKEY, OF MINNEAPOLIS, MINNESOTA.

SPARK-PLUG.

1,310,970.

Specification of Letters Patent. Patented July 22, 1919.

Application filed December 1, 1916. Serial No. 134,337.

To all whom it may concern:

Be it known that I, CHARLES M. STROUD, a citizen of the United States, residing at Minneapolis, in the county of Hennepin and State of Minnesota, have invented certain new and useful Improvements in Spark-Plugs; and I do hereby declare the following to be a full, clear, and exact description of the invention, such as will enable others skilled in the art to which it appertains to make and use the same.

My invention relates to spark plugs for explosive engines and provides an improved means for drawing an auxiliary charge, preferably of carbureted air, axially through the plug and against the electrodes, thereby keeping the latter clean of carbon and increasing the efficiency of the explosion.

In accordance with the invention, the spark plug is provided with an axial metal tube, the lower or inner end of which is preferably utilized as one of the electrodes; and within this axial tube, is a check valve that permits an inflow of vapor under the suction stroke of the piston, but checks a reverse flow under the force of the explosion. This valve is yieldingly closed by a coiled spring that is protected from the intense heat from the explosions, by the valve head, or ball and valve seat, both of which are located inward of the said spring. The sleeve-like plug body is provided with an electrode that cooperates with the end of the axial tube to afford the two electrodes of the plug; and the head of the valve is located immediately over and so closely adjacent to these electrodes that it will, when the valve is drawn into an open position, serve as a deflector to throw the hydro-carbon vapor over the entire surface of both electrodes.

The outer end of the axial tube of the plug is connected to the vapor intake manifold of the engine.

In the accompanying drawings which illustrate the invention, like characters indicate like parts throughout the several views.

Referring to the drawings;

Figure 1 is a plan view showing four plugs applied to a four-cylinder engine;

Fig. 2 is a side elevation of the improved plug; and

Fig. 3 is a vertical section taken centrally thereof.

The numeral 1 indicates the cylinder or cylinder casting, the numeral 2 the vapor

intake manifold, and the numeral 3 the carbureter of an ordinary four-cylinder explosive engine. The sparking plug proper comprises a metallic sleeve-like plug body 4 adapted to be screwed in the usual way into the head of the cooperating cylinder. Within the plug body 4 is a porcelain core 5 that is seated therein with a packed joint and held by means of an ordinary gland 6.

Extended axially through the core 5 is the metallic vapor conducting tube 7 that projects through said plug at both ends, and at its lower portion is provided with a collar 8 shown as seated in a recess formed in the lower end of said core. The upper end of the tube 7 is threaded and provided with a nut 9 between which and the upper end of the core, the packing 10 and a second nut 11 are interposed. The nut 9 also serves to connect to the outer end of the tube 7, one end of an elbow 12, the other end of which elbow is connected by a short rubber hose 13^a and a pipe 13 to the vapor intake manifold 3 of the engine. Of course, for a multi-cylinder engine, the pipe 13 will have branches leading to the elbows of the several plugs.

The short hose sections 13^a not only afford cheap couplings, but they serve as insulations to prevent the electro-forming tube 7 from being ground through the engine. The electric wire leading to the plug may be conveniently applied to the grooved head of a plug 12^a, which, as shown, is screwed into the top of the elbow 12. This plug 12^a, when removed, furthermore, affords access to the interior of the tube 7, and, consequently, to the nut 17 of the stem 16.

A short distance above its lower end, the axial tube 7 has a contracted valve seat 14 against which is normally seated the head 95 of a check valve 15. The head of this check valve is preferably spherical, and it is provided with a long stem 16 that extends through the valve seat and outward in the tube 7, and at its outer end is provided with an adjustable nut 17. A coiled spring 18 surrounds the valve stem 16 and is compressed between the back of the valve seat 14 and the nut 17. This spring, of course, normally holds the check valve closed.

Under the suction stroke of the engine, which, of course, draws the main charge of vapor into the cylinder through the customary intake port, an auxiliary charge of vapor will also be drawn into the cylinder 110

- through the axial tube 7. When the check valve 15 is drawn into its open position by suction, as stated, the hydrocarbon vapor drawn through said tube 7, will be sprayed 5 all around the lower end of said tube, to-wit, around that portion thereof that serves as one of the electrodes, and will also be sprayed over the other electrode 19, which, as shown, is in the form of a small metallic finger rigidly attached to the lower end of the plug body 4. Thus, the electrodes are washed 10 with the hydrocarbon vapor and kept clear of carbon, and moreover, the efficiency of the explosion is increased by this auxiliary 15 charge of vapor.
- The spring being outward of the valve head, its seat is protected from the intense heat from explosions and, furthermore, is kept cool by the stream of vapor drawn in 20 through the intake tube. This arrangement of the spring, in respect to the valve head and seat, is of the greatest importance, because in practice it has been found that where a spring is exposed to the direct heat 25 from the explosion, its temper will soon be drawn and the spring rendered useless. Also, the proximity of the valve head to the electrode of the plug, whereby the latter are well sprayed with the vapor, is of very great 30 importance.

The plug described is of simple construc-

tion and may be made of small cost. Its efficiency has been demonstrated in practice.

What I claim is:

A spark plug comprising a body, an insulating core therefor, a hollow fuel tube extending through the core and serving as an electrode, the lower end of said tube being open, a grounded electrode located beneath the open end of the tube, a valve arranged in the tube a slight distance above the lower end thereof and arranged, when open, to cause a spraying of the fuel against the wall of the tube, a valve stem extending upwardly through the fuel tube, and a closing spring for the valve encircling the stem and arranged within the tube, there being an annular space between the stem and the wall of the tube, whereby the fuel will be conveyed to all sides of the valve, said wall being arranged to direct the fuel against the grounded electrode and against that portion of the tube which acts as the second electrode, whereby the electrodes are kept free from carbon.

In testimony whereof I affix my signature in presence of two witnesses.

CHARLES M. STROUD.
